TOOTH STRAIGHTENING APPLIANCE

Application filed May 16, 1931. Serial No. 537,845.

This invention relates to an appliance which is designed to be used by orthodontists for correcting irregularities and faulty positions of teeth.

5 The object of the invention is to provide a very simple appliance which while exerting the required tension on the tooth or teeth to be corrected, permits free movements of the tooth or teeth during the stresses of mastication, stimulates the surrounding tissues and promotes bone development, the construction being such that it may be readily adapted to varying sizes and conditions of the mouths and teeth of adults and children, 10 and may be readily adjusted to exert the necessary degree of pressure and worn with a minimum amount of annoyance and discomfort.

In attaining this object bands shaped to fit 20 on anchor teeth are provided on their outer faces with small sheaths that have triangular openings which extend in line with the arch of the denture, and bands shaped to fit the teeth to be treated are provided with 25 small cleats that have triangular shaped outwardly facing openings. The anchor bands and a straightening band are fitted to the respective teeth and an arch wire of triangular cross section is passed around the outside 30 of the dental arch with its acute edge laid in the triangular shaped opening of the cleat on the straightening band and its ends thrust into the triangular openings in the sheaths on the anchor bands.

35 The arch wire is adjusted sufficiently close to the teeth to effect the required pressure on the tooth to be moved or straightened, and its ends fit the sheaths on the anchor bands sufficiently tight to ensure the necessary tension.

In the accompanying drawings Fig. 1 shows an upper denture with the improved straightening appliance arranged to correct an irregularity of an incisor. Fig. 2 shows 45 a side view of an anchor band and sheath. Fig. 3 shows a top view of an anchor band and sheath. Fig. 4 shows a side view of a straightening band and cleat. Fig. 5 shows a top view of a straightening band and cleat.

50 Fig. 6 is a detail view illustrating a means

that may be employed for holding an arch wire in a cleat on a straightening band.

In practicing this invention, as illustrated in the embodiment shown, bands 1 are shaped so that they may be readily fitted to the 55 teeth 2 which are chosen as the most suitable for anchoring the ends of the arch wire. Sheaths 3, preferably triangular in section, are secured by solder or otherwise to the outer faces of these bands. These sheaths 60 have openings 4 that are triangular in cross section, the openings extending through the sheaths in line with the arch of the denture and with the apexes of the triangles adjacent to the bands. 65

A band 5 is shaped so that it may be fitted to a tooth 6, the irregularity of which is to be corrected. On the outer face of this band is fastened, by solder or otherwise, a cleat 7 that has a triangular outward opening 8. 70 The arch wire 9, which is designed to exert the required pressure on the tooth to be corrected, is triangular in cross section and of a size to lie closely in the triangular opening in the cleat on the straightening band and to 75 fit tightly in the triangular openings in the sheaths on the anchor bands.

This triangular wire is bent around the outside of the denture with the apex of the triangle laid in the triangular opening in 80 the cleat on the tooth to be straightened, and the ends of the wire are thrust into the triangular openings through the sheaths on the anchor teeth. The wire is adjusted to a position which will cause it to exert the required tension on the irregular tooth. 85 Should it be desired to prevent the wire from springing out of the cleat a metal or floss filament 10 may be wound over the wire and about the projecting ends of the cleat, as illustrated in Fig. 6. Only one straightening band is illustrated but, of course, several could be used if necessary to accomplish the desired correction of the teeth.

The elements of this appliance are simple 95 and cheap to manufacture and apply. No complicated or projecting means, which are liable to cause irritation, are required for securing the arch wire in place. While the wire is capable of exerting the necessary force 100

to accomplish the required tooth movement, it does not grip and rigidly hold the teeth in such manner as to exclude the natural stresses of the teeth during mastication and thus prevent stimulation of the surrounding tissues. The triangular wire laid in the triangular cleat opening permits enough freedom during the processes of mastication to enable the teeth to function in accordance with the stresses to which they are subjected and to transmit those mechanical impulses to the surrounding tissues which will ensure arterial circulation and cell activity pertinent to new bone formation, as the tooth being straightened changes its relation to the jaw.

The invention claimed is:

1. A tooth straightening appliance comprising a pair of bands designed to be applied to anchoring teeth, said anchoring bands on their outer faces having sheaths with openings therethrough, a band designed to be applied to a tooth to be straightened, said straightening band on its outer face having a cleat with a triangular shaped outer opening, and an arch wire having an angular edge adapted to engage the inclined walls of the triangular opening in the said cleat with its ends closely fitting the openings in said sheaths.
2. A tooth straightening appliance comprising a pair of bands designed to be applied to anchoring teeth, said anchoring bands on their outer faces having sheaths with triangular openings, a band designed to be applied to a tooth to be straightened, said straightening band on its outer face having means with a triangular shaped outer opening, and an arch wire of triangular cross section with its apex inward, shaped and sized to fit the said openings.
3. A tooth straightening appliance comprising a pair of bands designed to be applied to anchoring teeth, said anchoring bands having on their outer faces sheaths with triangular openings, a band designed to be applied to a tooth to be straightened, said straightening band having on its outer face a cleat with a triangular shaped outer opening, and an arch wire that is triangular in cross section and is of a size to fit within the triangular outward opening in the said cleat and within the openings in said sheaths.

HERMAN LEVIN.
